UNITED STATES PATENT OFFICE.

JOHN A. GREER, OF NEPONSET, AND CLARENCE M. GREER, OF ELMHURST, ILLINOIS.

COMBINED ADVERTISING AND STATION-INDICATING DEVICE.

Application filed October 8, 1926. Serial No. 140,314.

Our invention relates to improvements in combined advertising and station indicating devices, and it consists in the combinations, constructions, and arrangements herein described and claimed.

An object of our invention is to provide a combined advertising and station indicating device which may be disposed at any desired position within the coach or car, preferably the forward end thereof, for attracting the attention of the passengers and announcing the name of the next station.

A further object of our invention is to provide a device of the type described which flashes a multiplicity of advertisements one at a time, these advertisements remaining in the observed position for a predetermined period of time, and then being automatically moved so as to bring the next advertisement into the observed position.

A further object of our invention is to provide a device of the type described in which the advertisement will automatically move in one direction at predetermined periods until the last advertisement has been drawn to the observed position, and then the device will automatically move the advertisements in the reverse direction.

A further object of our invention is to provide a device of the type described which will actuate an audible signal and automatically move the name of the next station into observed position when the conductor or operator presses a button.

A further object of our invention is to provide a device of the type described in which the station-indicating member will automatically reverse after the last station has been indicated, and the device is automatically set for the return trip.

Other objects and advantages will appear in the following specification, and the novel features of the invention will be particularly pointed out in the appended claims.

Our invention is illustrated in the accompanying drawings, forming part of this application, in which

Figure 1 is a front elevation of the device,

Figure 2 is a side elevation of the interior of the device,

Figure 3 is a plan view of the interior of the device,

Figure 4 is a wiring diagram,

Figure 5 is an enlarged view of a portion of the device,

Figure 6 is a diagrammatic view of a portion of the device,

Figure 7 is an enlarged plan view of a portion of the device,

Figure 8 is a section along the line 8—8 of Figure 7,

Figure 9 is a side elevation of that shown in Figure 7, and

Figure 10 is side elevations of cam rollers.

In carrying out our invention, we provide a casing 1 having openings 2 and 3 therein. A frame 4 is disposed in the casing and is provided with side walls 5 and 6. Rollers 7, 8, 9, and 10 are mounted upon shafts 7', 8', 9' and 10', respectively, which are rotatably mounted in the side walls 5 and 6 of the frame 4. A scroll 11 is provided having its ends wound upon the rollers 7 and 8. A metal contact roller 12 is rotatably disposed between the side walls 5 and 6 and permits the paper of the scroll to move thereupon. The roller 12 is insulated from the end walls of the frame by any suitable means. An idler roller 13 is rotatably disposed between the side walls 5 and 6 for receiving the paper of the scroll.

The scroll 11 is provided with a multiplicity of advertisements. The scroll 11 is further provided with an opening 15 which is positioned adjacent the first advertisement, an opening 16 which is positioned adjacent the last advertisement, and openings 17 which are disposed between each of the advertisements. A roller 18 is held in close engagement with the contact roller 12 at one end thereof. A roller 19 is disposed in engagement with the scroll 11 adjacent the roller 12 and in alignment with the opening 15 within the scroll. A roller 20 is disposed in engagement with the scroll 11 adjacent the roller 12 and in alignment with the opening 17 within the scroll. A roller 21 is disposed in engagement with the scroll 11 adjacent the contact roller 12 and in alignment with the opening 16 in the scroll 11.

A contact roller 22 is rotatably disposed between the side walls 5 and 6 and insulated therefrom by any suitable means. An idler roller 23 is rotatably disposed between the side walls 5 and 6. A scroll 24 having the names of stations printed thereupon is passed over the rollers 22 and 23 and wound upon the rollers 9 and 10. The scroll 24 is provided with an opening 25 which is disposed adjacent the first station name, an opening 105

26 which is disposed adjacent the last station name, and openings 27 which are disposed between each of the station names. A roller 28 is in engagement with the contact roller 22. A roller 29 is disposed in engagement with the scroll 24 adjacent the contact roller 22 and in alignment with the opening 25. A roller 30 is disposed in engagement with the scroll 24 adjacent the contact roller 22 and in alignment with the openings 27. A roller 31 is disposed in engagement with the scroll 24 adjacent the contact roller 22 and in alignment with the opening 26.

15 A motor 32 is mounted upon the frame 4 and provided with a relatively small gear 33 and a worm 34. A relatively large gear 35 which is rigidly mounted upon a shaft 36 is in mesh with the gear 33. Worms 37, 38, 39, and 40 are rigidly mounted upon the shaft 36 and are in mesh with worm gears 41, 42, 43, and 44, respectively. The worm gears 41 to 44 inclusive are rigidly mounted upon the shafts 7', 8', 9' and 10', respectively.

20 The worm 34 is operatively connected to a shaft 45 by means of a worm gear 46 which is in mesh with the worm 34, a worm 47, and a worm gear 48 which is in mesh with the worm 47. A cut-out cam roller 49 and a cut-in cam roller 50 are rigidly mounted upon the shaft 45. The cam roller 49 is provided with a cutaway portion 51. The cam roller 50 is provided with an outwardly extending lug 52. Resilient contact points 53 are disposed in engagement with the cam roller 49. Resilient contact points 54 are disposed adjacent the cam roller 50 and are adapted to contact with the outwardly extending lug 52 thereupon. A ratchet wheel 55 is rigidly mounted upon the shaft 45. A sleeve 56 is disposed concentric with the shaft 45 between the cam roller 50 and the ratchet wheel 55. A cut-out cam roller 57 and a cut-in cam roller 58 are rigidly mounted upon the sleeve 56. The cam roller 57 is provided with a recess 59, and the cam roller 58 is provided with an outwardly extending lug 60. Contact points 61 are disposed in engagement with the cam roller 57, and contact points 62 are disposed substantially adjacent the cam roller 58 and are adapted to contact with the outwardly extending lug 60 thereupon. A pawl 63 is pivotally mounted upon a disc 63^a which is rigidly mounted upon the sleeve 56. The pawl is adapted to be moved into engagement with the ratchet wheel 55. The pawl 63 is provided with a transversely extending portion 63^b which is arranged to engage with a plunger 63^c of a core 63^d. A flat spring 63^e is arranged to stop the movement of the pawl 63, the sleeve 56 and the members thereon. The spring 63^e also forces the pawl into engagement with the ratchet wheel 55. A tension spring 63^f is provided for moving the core 63^d and the plunger 63^c toward the pawl and for normally holding the plunger in en-

gagement with the pawl. A source of current indicated at 64 is provided for the motor 32, and may be cut off from the motor by means of a switch 65.

25 In Figure 4, we have shown a wiring diagram illustrating the manner in which the scrolls are automatically moved. A clutch 66 is disposed in engagement with the roller 7 and is adapted to engage the roller 7 with the worm gear 41 when in closed position. A metal contact disc 67 is carried by the clutch 66 and insulated therefrom. A solenoid is provided having a core 68 which is secured to the clutch 66, a coil 69, and a coil 70. In like manner, a clutch 71 is disposed in engagement with the roller 8 and is provided with a metal contact disc 72 which is insulated therefrom. A solenoid is provided having a core 73 secured to the clutch 71 and coils 74 and 75.

30 A battery 76 is provided. A solenoid 77 is provided for transmitting the source of current from the solenoid for actuating one of the clutches to the solenoid for actuating the other clutch. The solenoid 77 consists of a core 78 and coils 79 and 80. Contact discs 81, 82, 83 and 84 are secured to the core 78 and insulated therefrom. Conductors 85 and 86 direct the source of current from the battery 76 to the coil 75. As the source of current flows through the coil 75, the clutch 71 is moved into closed position.

35 A conductor 87 is provided for directing the source of current from the coil 75 to and through the contact disc 83 to a conductor 88 which directs the source of current to the cut-in cam roller 50. Conductors 89, 90 and 91 are provided for directing the source of current from the cut-in cam roller 50 back to the battery 76 when the lug 52 contacts with the conductors 88 and 89. This is the means for automatically actuating the roller 8 and winding the scroll 11 thereupon.

40 A conductor 92 directs the source of current from the conductor 86 to and through the coil 74. As the source of current passes through the coil 74, the core 73 is moved so as to move the clutch 71 into opened position. The source of current after passing through the coil 74 passes through a conductor 93, through the contact disc 72, and a conductor 94 to the cut-out cam roller 49. A conductor 95 directs the source of current from the cut-out cam roller 49 to the roller 20. When the roller 20 contacts with the roller 12, the source of current passes through the roller 12 to and through the roller 18. The source of current passes from the roller 18 through the conductor 90, the conductor 91, and to the battery 76. In this manner, the roller 8 is released from the worm gear 42 and remains stationary until the clutch 71 is again moved into closed position.

45 A similar means is provided for actuating the scroll 24 which is disposed upon the rollers 9 and 10. A clutch 96 is disposed in en-

gagement with the roller 9 and provided with a contact disc 97. A solenoid is provided having a core 98 which is secured to the clutch 96, and coils 99 and 100. A clutch 101 is operatively connected to the roller 10 and is provided with a contact disc 102. A solenoid is provided having a core 103 which is secured to the clutch 101, and coils 104 and 105.

Means is provided for automatically cutting off the source of current from one of the solenoids in operative connection with the clutches 96 and 101 and permitting the source of current to flow through the other solenoid. This means includes a solenoid 106 having a core 107, and coils 108 and 109. Contact discs 110, 111, 112, and 113 are operatively connected to the core 107 and are adapted to move therewith.

In Figure 5, we have shown a detailed view of the clutch 66 which is identical in construction to the clutches 71, 96, and 101, and a description of one will apply to them all. The clutch 66 is provided with an annular groove 114. A pawl 115 is pivotally mounted upon a bracket 116 which is rigidly mounted upon the worm gear 41. The pawl passes through an opening in the worm gear which permits the pawl to move freely inwardly and outwardly and is disposed in a position so as to engage with the clutch 66. When the pawl 115 engages with the clutch 66, the lug 117 of the pawl is received in the annular groove 114 of the clutch. In this manner, the pawl is temporarily held in opened position. A gear 118 is rigidly secured to the roller 7 and is positioned whereby the pawl 115 engages therewith when released by the clutch. This is a means for operatively connecting the roller 7 with the shaft 36 of the driving mechanism.

From the foregoing description of the various parts of the device, the operation thereof may be readily understood. The casting 1 is secured in any desired position, preferably at the fore end of the coach or car. When the switch 65 is closed, the scroll 11 is automatically actuated. Assume that the scroll is moving in the direction of the arrow 119. During this movement, the clutch 71 is in closed position and the scroll continues in its movement until one of the openings 17 in the scroll moves into alignment with the roller 20. In this manner, the roller 20 is permitted to contact with the roller 12, thus closing the circuit which permits the source of current to pass through the coil 74 of the solenoid and move the core 73, together with the clutch 71, into opened position. This frees the roller 8 from the driving mechanism permitting the scroll to remain in the stopped position until the cut-in cam roller 50 rotates to a position whereby the lug 52 will contact with the contact points 54. This closes the circuit and permits the

source of current to pass through the coil 65 75, thus moving the core 73 and the clutch 71 into closed position, thus again connecting the roller 8 with the driving mechanism. This operation is continued until the opening 15 in the scroll, which is adjacent the 70 end thereof, moves into a position adjacent the roller 19. At this point, the roller 19 is permitted to contact with the roller 12, thus closing the circuit and permitting the source of current to flow through the coil 79, and 75 causing the core 78, together with the contact discs 81 to 84 inclusive, to move inwardly. By so doing, the circuits for actuating the clutch 71 are cut off, and the circuits for actuating the clutch 66 are now permitted to 80 be opened and closed by the cut-in cam roller 50 and the cut-out cam roller 49.

When the cut-in cam roller 50 rotates to a position whereby the lug 52 contacts with the contact points 54, the circuit is closed 85 permitting the source of current to pass from the battery through the conductors 91, 90, 89, 88, 120, the contact disc 84, a conductor 121, through the coil 70, a conductor 122, the conductors 86 and 85, back to the battery. 90 As the source of current flows through the coil 70, the clutch 66 and the core 68 are moved inwardly into closed position. This engages the roller 7 with the driving mechanism and causes the scroll 11 to move in the 95 reverse direction. The scroll continues its movement in this direction which is indicated by the arrow 123 until one of the openings 17 moves into a position adjacent the roller 20. At this point, a circuit is closed permitting 100 the source of current to pass from the battery through the conductors 91, 90, through the rollers 18, 12, and 20, through the conductor 95, the cut-out cam roller 49, the conductor 94, a conductor 124, through the contact disc 105 67, through the coil 69, and through the conductors 92, 86 and 85, back to the battery.

As the source of current passes through the coil 69, the core 68 and the clutch 66 are moved outwardly disengaging the roller 7 110 from the driving mechanism. This operation is continued until the opening 16 within the scroll 11 is moved to a position adjacent the roller 21. The roller 21 is then permitted to contact with the roller 12, thus closing a circuit and permitting the source of current to pass from the battery through the conductors 91, 90, the rollers 18, 12 and 21, through a conductor 125, through the contact disc 82, the coil 80, a conductor 126, and the conductor 120 85 to the battery. As the source of current passes through the coil 80, the core 78, together with the contact discs 81 to 84 inclusive, are moved outwardly, thus cutting off the circuits for actuating the clutch 66 and 125 permitting the cut-in cam roller 50 and the cut-out cam roller 49 to again close the circuits for actuating the clutch 71. The scroll

is then moved in the direction of the arrow 119. At each movement of the scroll 11, a different advertisement is displayed.

The scroll 24 is actuated in substantially the same manner as the scroll 11. However, instead of continually moving, the scroll 24 is only moved at desired times, as for instance, when a car is approaching a station. To actuate the scroll 24, the operator presses a button 10 ton or switch 127 closing a circuit and permitting the source of current to pass from the battery through the conductor 85, through the switch 127, a conductor 128, an audible signal 129, a coil 130 which is wound around the core 63^a, and through the conductors 131, 89, 90 and 91, and back to the battery.

In this manner, the plunger 63^c is withdrawn from the pawl 63 against the tension of the spring 63^f, the pawl 63 is moved into engagement with the ratchet wheel 55 by the spring 63^a, and the cut-in cam roller 58 and the cut-out cam roller 57 are rotated. As the cut-in cam roller 58 is rotated, the integral lug 60 thereupon is moved into contact with the contact points 62, thus closing the circuit permitting the source of current to pass from the battery 76 through the conductor 85, the conductors 136 and 137, through the coil 104, the conductor 133, through the contact disc 112, through the conductor 132, the cut-in cam roller 58 and the conductors 131, 89, 90 and 91 back to the battery.

As the source of current passes through the coil 104, the core 103 and the clutch 101 are moved outwardly engaging the roller 10 with the driving mechanism, thus causing the scroll 24 to move in the direction of the arrow 135.

The scroll moves in this direction until one of the openings 27 is adjacent the roller 30. This permits the roller 30 to contact with the roller 22 which closes the circuit for permitting the source of current to pass through the coil 105 and move the core 103, together with the clutch 101, inwardly. This movement of the clutch disengages the roller 10 from the driving mechanism and permits the scroll to stop. This operation is continued until the opening 25 within the scroll is moved into alignment with the roller 29. This permits the roller 29 to contact with the roller 22, thus closing a circuit for permitting the source of current to flow through the coil 109 and move the core 107, together with the contact discs 110 to 113 inclusive, inwardly. This operation cuts off the currents for actuating the clutch 101 and permits the cut-in cam roller 58 and the cut-out cam roller 57 to close circuits for actuating the clutch 96. The clutch 96 engages and disengages the roller 9 with the driving mechanism, thus causing the scroll to move in the reverse direction.

This operation is continued until the opening 26 within the scroll 24 is moved into a

position adjacent the roller 31. This permits the roller 31 to contact with the roller 22, thus closing a circuit and permitting the source of current to pass through the coil 108. As the source of current passes through the coil 108, the core 107, together with the contact discs 110 to 113 inclusive, is moved outwardly cutting off the circuits for actuating the clutch 96 and permitting the cut-in cam roller 58 and the cut-out cam roller 57 to close circuits for actuating the clutch 101.

The names of the different stations are placed upon the scroll 24 between the openings 27. Upon approaching each station, the scroll 24 is actuated to bring the name of that station into alignment with the opening 2. When the last station has been reached and the name of that station has been brought into alignment with the opening 2, the opening 25 has also been brought into a position adjacent the roller 29. Therefore, upon starting the return trip, the scroll is automatically set in readiness to indicate the stations.

Assuming that the train upon which the device is used stops at all the stations during one trip but becomes an express and skips several stations upon the return trip, a special means is employed for causing the scroll 24 to be automatically and continuously actuated until the name of the next station at which the train is to stop is brought into view. This means includes a dial 138 having segments thereon, each segment representing one of the stations indicated upon the scroll 24. The dial 138 is operatively connected to a contact hand 139 and is adapted to move the hand when the dial is moved. A circular contact plate 140 is disposed concentric with the dial 138 and in the path of the end of the contact hand 139. A contact block 141 is positioned between the ends of the contact plate 140 and is in electrical connection with the contact point 61 by means of a conductor 142. A ratchet wheel 143 is operatively connected to the dial 138 and the contact hand 139 and is adapted to move therewith. A weight pawl 144 is adapted to engage with the ratchet wheel 143 and is pivotally mounted upon one end of a lever 145. The lever 145 is pivoted at 146 and is held in a downward position by means of a tension spring 147 and the weight pawl 144. A magnetic coil 148 is positioned adjacent the free end of the lever 145, one end of the coil being in electrical connection to the contact plate 140, the other end of the coil being in electrical connection with the conductor 85 and the battery 76.

Assuming that the operator wishes to bring into view the name of the fourth station from that which is already in view, owing to the fact that a train is to pass by these stations without stopping, the operator turns the dial until the segment 4 is in alignment with an indicating point 149. The operator then presses the button 127, causing the scroll 24

to be actuated in the manner heretofore described. As the scroll is actuated and the opening 27 comes into alignment with the roller 30, the circuit is closed, permitting the 5 source of current to pass from the battery through the conductor 85, the magnet 148, the contact plate 140, the contact hand 139, the conductor 138, the rollers 30, 22 and 28, and the conductor 91, back to the battery. As 10 the source of current passes through the magnet 148, the pawl 144 is raised upwardly and held in this position until the scroll 24 moves so as to separate the roller 30 from the roller 22, thus breaking the circuit and permitting 15 the pawl to move downwardly and move the sprocket wheel one notch. This operation is continued until the sprocket wheel is moved so as to bring the contact hand 139 back into engagement with the contact block 141. It 20 will be observed that each time one of the openings 27 comes into alignment with the roller 30, the pawl 144 will be actuated, and, when released, the pawl will move the sprocket wheel and the contact hand the dis- 25 tance of one tooth. This mechanism prevents the source of current from flowing through the cut-out cam roller 57 so as to release the clutch 101. When the contact hand 139 has been returned to its normal position, the 30 device is actuated in the usual manner heretofore described.

The contact hand 139 remains in contact with the contact plate 140 after the dial 138 has been returned to the second indication 35 thereon. Therefore the above mentioned circuit for actuating the magnet 148 will be closed, thus raising the pawl 144. When the circuit is again broken, the spring 147 will bring the pawl into engagement with the 40 ratchet wheel. The force of the spring will rotate the sprocket 143, thus bringing the dial into its normal position and the contact hand into engagement with the block 141.

We claim:

45 1. A device of the type described comprising a display scroll, a pair of roller shafts, rollers mounted upon said roller shafts, said scroll disposed upon said rollers, a drive shaft, means for rotating said drive shaft, a driven shaft operatively connected to said drive shaft, ratchet wheels rigidly mounted upon said roller shafts, a worm gear rotatably carried by each of said roller shafts, worms rigidly mounted upon said driven shaft and in mesh with said worm gears, a pawl pivotally carried by each of said worm gears and arranged to be moved into and out of registration with their respective ratchet wheels, and means for moving 50 one of said pawls into engagement with one of said ratchet wheels for moving said scroll in one direction, said pawl-actuating means being arranged to move said pawl out of engagement with said ratchet wheel for stopping the movement of said scroll.

2. A device of the type described comprising a display scroll, a pair of rollers, said scroll disposed upon said rollers, a drive shaft means for rotating said drive shaft, a driven shaft operatively connected to said drive shaft, a ratchet wheel carried by each of said rollers, a worm gear rotatably carried by each of said rollers, worms rigidly mounted upon said driven shaft and in mesh with said worm gears, a pawl pivotally carried by each of said worm gears and arranged to be moved into and out of registration with their respective ratchet wheels, means for moving one of said pawls into engagement with one of said ratchet wheels for moving 70 said scroll in one direction, said pawl-actuating means being arranged to move said pawl out of engagement with said ratchet wheel for stopping the movement of said scroll, and means for moving the other pawl into engagement with the other ratchet wheel for moving the scroll a predetermined distance in the opposite direction, said second named pawl-moving means being arranged to move said second named pawl out of engagement with said second named ratchet wheel for stopping said scroll. 75

3. In a device of the type described, a scroll, a roller for said scroll, a ratchet wheel rigidly carried by said roller, a worm gear rotatably carried by said roller, a drive shaft, means for rotating said drive shaft, a driven shaft, a worm rigidly mounted upon said driven shaft and in mesh with said worm gear, a bracket mounted upon said worm gear, a pawl pivotally carried by said bracket and arranged to be moved into registration with said ratchet wheel, and means for moving 90 said pawl out of registration with said ratchet wheel. 95

4. A device of the type described comprising a display scroll, a roller for receiving said scroll, a drive shaft, means for rotating said drive shaft, a driven shaft operatively connected to said drive shaft, a clutch for operatively connecting said roller to said driven shaft, means for actuating said clutch for connecting and disconnecting said roller with and from said driven shaft, whereby 100 said scroll will be moved intermittently in one direction, said means including a cam shaft operatively connected to said drive shaft, a cut-in cam roller rigidly mounted upon said cam shaft, contact points arranged to engage with said cut-in cam roller at a predetermined point thereupon, electrically-operated means for actuating said clutch for connecting said roller to said drive shaft for moving said scroll, said contact points being 105 electrically connected to said electrically-operated means for closing a circuit for permitting a source of current to pass through said electrically-operated means when said contact points engage with said cut-in cam roller, electrically-operated means for actuating 110

said clutch for disconnecting said roller from said driven shaft, a cut-out cam roller rigidly mounted upon said cam shaft, a second set of contact points electrically connected to said 5 second named electrically-operated means and disposed in engagement with said cut-out cam roller; an indicating scroll, a roller for said indicating scroll, a clutch arranged to engage and disengage the roller for said indicating scroll with and from said driven shaft; electrically-operated means for actuating said clutch; a sleeve rotatably mounted upon said cam shaft; a second cut-in cam roller rigidly mounted upon said sleeve and 10 arranged to electrically connect said last named electrically-operated means with a source of current for connecting said clutch; a second named cut-out cam roller rigidly mounted upon said sleeve and arranged to 15 electrically connect said last named electrically-operated means with a source of current for disconnecting said clutch; and means for connecting said sleeve with said cam shaft.

5. In a device of the type described, a scroll, 20 a drive shaft, means for rotating said drive shaft, a driven shaft operatively connected to said drive shaft, electrically-operated means for connecting said scroll with said

driven shaft for moving said scroll a predetermined distance, electrically-operated means for disconnecting said scroll from said driven shaft for stopping the movement of said scroll, and electrically-operated means for moving said scroll for a desired number of the predetermined distances, said means comprising a ratchet wheel, a conductor carried by said ratchet wheel, a contact block carried by said ratchet wheel and spaced away from said conductor, a contact point, a lever, a pawl carried by said lever, spring 30 means operatively connected to said lever for moving said pawl into engagement with said ratchet wheel for moving said ratchet wheel a predetermined distance, and electrically-operated means electrically connected to said contact point for actuating said lever for moving said pawl away from said ratchet wheel, the movement of said ratchet wheel breaking the circuit for actuating said electrically-operated means, thereby releasing 35 said lever for allowing said pawl to engage with said ratchet wheel for moving said contact block into engagement with said contact point.

JOHN A. GREER.

CLARENCE M. GREER.
